Attorney, Agent, or Firm—Fulwider Patton Lee & Utecht, LLP

[57] CLAIM

The ornamental design for a light fixture, as shown and described.

DESCRIPTION

FIG. 1 is a broken bottom perspective view showing my new design;

FIG. 2 is a broken front view, in enlarged scale, thereof;

FIG. 3 is a broken bottom view, in enlarged scale, thereof;

FIG. 4 is a right hand end view, in enlarged scale, thereof;

FIG. 5 is a broken top view, in enlarged scale, thereof; and,

FIG. 6 is a left end view, in enlarged scale, thereof.

The light fixture is broken away in FIGS. 1, 2, 3 and 4 to indicate indeterminate length.

[63] Continuation-in-part of application No. 29/104,949, May 17, 1999.
